RAKE

Christian F. Hess, Wilmette, Ill.

Application June 5, 1941, Serial No. 396,643

5 Claims. (Cl. 56—400.01)

This invention relates to improvements in rakes for raking leaves, trash, lawns, and for similar purposes, and one of the objects of the same is to provide an improved light, simple, inexpensive and efficient rake in which any one or more of the teeth may be readily removed and replaced by another tooth without interfering with or detaching any of the other teeth from the rake head.

A further object is to provide an improved rake of this character in which the teeth are so shaped as to prevent injury to the lawn.

A still further object is to provide an improved form of tooth and improved means for fastening or securing the same to the head or body of the rake.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a front elevation of a rake of this character constructed in accordance with the principles of this invention.

Figure 2 is an end elevation of Figure 1.

Figure 3 is a detail sectional view taken on line 3—3 Figure 1, on an enlarged scale.

Figure 4 is an elevation of a portion of the rake taken from the rear face thereof.

Figure 5 is a detail sectional view taken on line 5—5 Figure 4, on an enlarged scale.

Figure 6 is a detail perspective view of a portion of the head plate showing the manner of attaching or detaching the tooth therefrom.

Figure 7 is a detail perspective view of a portion of the tooth fastening bar.

Figure 8 is a detail perspective view of the forward or free end of one of the teeth.

Figure 9 is a detail perspective view of a portion of a tooth of a modified form.

Referring more particularly to the drawing, the numeral 10 designates generally a head plate which may be of any desired size and configuration and constructed of any suitable material such for instance as metal, and the plate is considerably longer than it is wide.

One of the longitudinal edges of the plate is bent back upon itself, as at 11, to form a seat 12 and the edge 13 of the portion 11 terminates considerably short of the opposite edge of the plate.

If desired, a reinforcing bar 14 may be secured

to one edge of the plate by rolling a portion of the plate thereover.

A number of slots 15 are provided in the portion 11 of the plate and these slots open through the edge 13, the slots being spaced from each other in directions lengthwise of the plate. Portions of the plate are struck out, as at 16, to form openings 17 and these struck out portions 16 form arches extending transversely of the longitudinal dimension of the plate so as to provide openings through the sides of the struck out portions.

These openings thus formed are preferably spaced for a substantial distance beyond the edge 13 of the portion 11 of the plate and are arranged in cooperating pairs.

The teeth of the rake are separate from each other and each tooth 18 is formed of resilient material bent into a substantially U shaped configuration with a rounded extremity 19. The

extremities of the sides of each tooth are deflected laterally, as at 20 and the space between adjacent openings 17 is less than the normal distance between the extremities of the sides of the tooth so that in order to attach the tooth to the

plate 10, it is necessary to force the extremities of the side members of the tooth toward each other into the position shown in full lines in Figure 6. The tooth may then be attached to the plate 10 by positioning the laterally deflected portions 20 between the cooperating arch shaped portion 16 so that when pressure is released upon the sides of the tooth the normal tendency of the resiliency of the material of which the tooth is constructed will separate the extremities and cause the deflected portions 20 to engage under the arch shaped portion 16.

In this position the tooth may be swung about the extremities 20 as pivots and into a position that each of the sides of the tooth will enter one of the slots 15 in the bent back portion 11 of the plate 10.

The numeral 21 designates a tooth fastening bar and this bar, when the teeth are in the position as shown in Figures 3 and 6, may be placed in the seat 12 behind the bent back portion 11 to extend across the teeth and thereby not only hold the teeth against swinging movement about their pivots but will also form a closure for the slots 15.

This fastening bar or plate 21 may be secured in position in any desired or suitable manner such as by means of fastening devices or screws 22 passing through suitable openings 23 in the bar and engaging in suitable openings 24 in the plate 10.

With this construction it will be manifest that should any one of the teeth become broken or damaged, it can be readily removed and replaced by another tooth, by first removing the fastening devices 22 of the fastening bar 21 and then removing the bar itself, after which the tooth may be swung from the position shown in dotted lines in Figure 6 to the position shown in full lines, and the pivoted extremities of the side members of the tooth forced towards each other so as to pass from under or disengage the arch shaped portion 16 on the plate 10.

The forward extremity of each of the teeth is preferably deflected laterally, as at 25, and the teeth may be of any desired length.

In Figure 9 there is shown a modified form of tooth in which there is provided in each of the side members 26 a coil 27, and the extremities of the side members 26 are also deflected laterally as at 28 so that they may be detachably secured or connected to the plate 10.

Any suitable means may be provided for securing a handle 29 to the head plate 10, such as by means of a socket or ferrule 30 which is preferably of tubular configuration and is provided with a head 31 at one end thereof. Projecting from the head are any desired number of ears or lugs 32 which are adapted to be inserted into openings 33 in the head plate 10 (see particularly Figure 5) and are then flanged down upon the plate 10.

If desired, the tubular portion of the socket 30 may be provided with a notch or recess 34 to receive the reinforced edge of the plate 10.

The end of the handle 29 is inserted in the socket 30 and may be secured against detachment therefrom in any suitable manner such as by means of a fastening screw or member 35.

With this improved construction it will be manifest that there will be provided a very light and efficient rake, the teeth of which are resilient and are so shaped that the free extremities thereof will not injure the lawn or grass. At the same time the teeth are attached to the head or plate 10 in such a manner that any one or more of them may be removed without interfering with the other teeth, and a new tooth inserted.

While the preferred forms of the invention are herein shown and described, it is to be understood that various changes may be made in the details of construction and in the combination and arrangement of the several parts, within the scope of the claims, without departing from the spirit of the invention.

What is claimed as new is:

1. A rake embodying a head member comparatively long with respect to its width, one edge of which is bent back upon itself into a plane substantially parallel with the body portion to form a channel, the edge of said bent-back portion terminating considerably short of the other edge of said body, there being spaced openings in said bent-back portion extending through the free edge thereof and also through the bottom of said channel, there being spaced openings in said body spaced from the free edge of said bent-back portion, substantially U-shaped tines, the free extremities of the sides of which are deflected laterally and adapted to enter the last said openings to hingedly connect the tines to said body, each side of said tines being seated in and passing through one of the openings in said bent-back portion, a fastening member of substantial width seated in said channel between one face of the tines and the adjacent face of said bent-back portion to hold the tines firmly against said body.

portion, and to form a closure for the openings in said bent-back portion, and means for releasably securing said fastening member in position.

2. A rake embodying a head member comparatively long with respect to its width, one edge of which is bent back upon itself into a plane substantially parallel with the body portion to form a channel, the edge of said bent-back portion terminating considerably short of the other edge of said body, there being spaced openings in said bent-back portion extending through the free edge thereof and also through the bottom of the channel, there being spaced openings in said body intermediate the free edge of said bent-back portion and the said other edge of the body, substantially U-shaped tines formed of resilient material, the free extremities of the sides of which are deflected laterally to enter the last said openings to hingedly connect the tines to said body, the distance between the adjacent last said openings being less than the normal distance of the deflected extremities of the sides of said tines, whereby the said extremities must be sprung into their respective openings, each side of the tines being seated in and passing through one of the openings in said bent-back portion, and removable fastening means disposed between one face of the tines and the adjacent face of said bent-back portion to hold the tines against the face of said body.

3. A rake embodying a head member comparatively long with respect to its width, one edge of which is bent back upon itself into a plane substantially parallel with the body portion to form a channel, the edge of said bent-back portion terminating considerably short of the other edge of said body, there being spaced openings in said bent-back portion extending through the free edge thereof and also through the bottom of the channel, there being spaced openings in said body formed by striking out portions of the body and disposed intermediate the free edge of said bent-back portion and the said other edge of the body, substantially U-shaped tines formed of resilient material, the free extremities of the sides of which are deflected laterally to enter the last said openings to hingedly connect the tines to said body, the distance between the adjacent last said openings being less than the normal distance of the deflected extremities of the sides of said tines, whereby the said extremities must be sprung into their respective openings, each side of the tines being seated in and passing through one of the openings in said bent-back portion, and removable fastening means disposed between one face of the tines and the adjacent face of said bent-back portion to hold the tines against the face of said body.

4. A rake embodying a head member comparatively long with respect to its width, one edge of which is bent back upon itself into a plane substantially parallel with the body portion to form a channel, the edge of said bent-back portion terminating considerably short of the other edge of said body, there being spaced openings in said bent-back portion extending through the free edge thereof and also through the bottom of the channel, there being spaced openings in said body intermediate the free edge of said bent-back portion and the said other edge of the body, substantially U-shaped tines formed of resilient material, the free extremities of the sides of which are deflected laterally to enter the last said openings to hingedly connect the tines to said body.

the tines to said body, the distance between the adjacent last said openings being less than the normal distance of the deflected extremities of the sides of said tines, whereby the said extremities must be sprung into their respective openings, each side of the tines being seated in and passing through one of the openings in said bent-back portion, and removable fastening means disposed between one face of the tines and the adjacent face of said bent-back portion 10 to hold the tines against the face of said body, the sides of said tines intermediate their free ends and the adjacent edge of said body, and in proximity to the last said edge being formed into loops to impart further resiliency to the 15 tines.

5. A rake embodying a head member comparatively long with respect to its width, one edge of which is bent back upon itself into a plane substantially parallel with the body portion to form a channel, the edge of said bent-back portion terminating considerably short of

the other edge of said body, there being spaced openings in said bent-back portion extending through the free edge thereof and also through the bottom of said channel, there being spaced 5 openings in said body spaced from the free edge of said bent-back portion, substantially U-shaped tines, the free extremities of the sides of which are deflected laterally and adapted to enter the last said openings to hingedly connect the tines to said body, each side of said tines being seated in and passing through one of the openings in said bent-back portion, a fastening member of substantial width seated in said channel between one face of the tines and the adjacent face of said bent-back portion to hold the tines firmly against said body portion, and to form a closure for the openings in said bent-back portion, means for releasably securing said fastening member in position, and a re-enforcing member 10 extending along and secured to the said other side of said body.
